TUBE BEADING DEVICE FOR TAMPON
APPLICATORS AND THE LIKE

John R. McLaughlin, New Brunswick, N. J., assignor to Tampax Incorporated, New York, N. Y., a corporation of Delaware

Application October 23, 1942, Serial No. 463,097

4 Claims.

(Cl. 93—77)

The present invention relates to apparatus for beading or rounding the ends of the cylindrical walls of tubes. The invention more specifically appertains to a machine for beading the ends of tubes to permit the ready insertion of one tube telescopically into another tube of larger dimensions. Tubes telescoped in this manner are adapted to provide an applicator in which a cotton wad is confined in a compressed state for use for sanitary purposes or otherwise.

It is an object of the present invention to simplify the construction and improve the operation of an apparatus of the character contemplated herein.

It is another object of the invention to provide an apparatus that is adapted for continuous operation whereby the beading of the tubes may be performed in a rapid manner and in relatively large quantities.

A still further object of the invention is to provide an apparatus that is of comparatively simple construction and possesses a high degree of novelty and efficiency.

Still another object is the provision of an apparatus of the character contemplated herein that is effective in performing its functions, and is dependable in its manner of operation.

A still further object is the provision of an apparatus that is capable of handling and operating upon tubes that are made from paper and like material without damage to the paper or distortion to the shapes of the tubes.

Additional objects, aims, and advantages of the present improvements will be apparent to persons skilled in the art after the invention is understood from the within description. Among these additional objects may be mentioned that it is an aim to provide an apparatus that is made of sturdy parts so that it will be capable of withstanding severe usage and continuous operation, and which is comparatively economical to manufacture.

It is preferred to accomplish the above-mentioned and other objects, and to practice this invention, in substantially the manner herein fully described and as more particularly pointed out in the appended claims, reference being hereby made to the accompanying drawings that form a part of this specification.

In the drawings:

Figure 1 is a fragmentary plan view of the operating instrumentalities for rounding the ends of the tubes.

Figure 2 is a side view of the instrumentalities shown in Figure 1.

Figure 3 is an end view in elevation of the

instrumentalities shown in Figure 1 as viewed from the opposite side shown in Figure 2.

Figure 4 is a front view in elevation of the cam element in disassembled relation to the other 5 instrumentalities appearing in Figure 2.

Figure 5 is a side view in elevation of one of a pair of tube-holding levers shown in assembled association in Figure 1.

Figure 6 is a plan view of the tube-holding lever 10 shown in Figure 5.

Figure 7 is a sectional view taken substantially along line VII—VII of Figure 6.

Figure 8 is a plan view of the inner tube of a 15 pair of tubes prior to having the ends rounded, the parts thereof being shown in section to clarify the illustration.

Figure 9 is a plan view of the inner tube shown in Figure 8 after its ends have been rounded, the parts thereof being shown in section to clarify 20 the illustration.

Figure 10 is a fragmentary sectional view of the assembled tubes and a sanitary cotton plug in relationship to the rounded ends with reference to the compressed sanitary plug assembled 25 therewith.

Figure 11 is a fragmentary sectional view taken substantially along line XI—XI of Figure 1.

Figure 12 is a fragmentary sectional view taken substantially along line XII—XII of Figure 1.

30 Figure 13 is a fragmentary sectional view taken substantially along line XIII—XIII of Figure 1.

Figure 14 is a fragmentary sectional view taken substantially along line XIV—XIV of Figure 1.

35 Figure 15 is a fragmentary sectional view taken substantially along line XV—XV of Figure 3.

The drawings, which are to be understood as being more or less of a schematic character, disclose a typical or preferred form in which the invention may be made, and in these drawings the 40 same reference characters are employed for the purpose of identification of like parts wherever the same parts appear in the divers views.

The structure which has been selected for illustration is intended for rounding or beading the 45 ends of tubes 10 (Figures 9 and 10) which comprises one of a pair of tubes that are telescoped to provide a unit such as a paper applicator which is adapted to confine within it a wad of cotton or the like for use for sanitary purposes such as the type which is disclosed and described in United States Letters Patent No. 2,024,218. In this particular instance, the tube 10 as well as its coating tube 11 is constructed of disposable paper material so that the rounding or beading of the ends

50 of the tube wall must be effected without impair-

ment to the structure of the body of the tube. As fragmentarily shown in section in Figure 10, the tube 10 with its rounded or beaded end is telescopically entered into the outer tube 11, which preferably surrounds the cotton wad 12 and effectively retains said wad in compressed condition and ready for use.

In the present embodiment of the apparatus, a supporting base 14 provides the bottom or floor of a rectangular bin 15 which provides a confining medium for a quantity of the tubes 10 which are dumped therein without predetermined arrangement to effect gravity feeding thereof to instrumentalities to be hereinafter described. A suitable chute 16 inclines downwardly away from an exterior portion of the bin 15 and the lower bed portion of said chute 16 is curved downwardly to provide a discharge throat 17 in the manner shown in Figures 2, 3, and 11. The tubes 10, as shown in Figures 2, 11 and 15 are disposed transversely across the chute 16 and the discharge throat 17, and they are stacked in a successive row with their sides contacting each other.

Beneath the discharge throat 17 of the chute 16 there is a table structure which supports the instrumentalities for beading the ends of the tubes. This table embodies a horizontal shelf 18 of sheet metal, preferably of a heavy gauge and of rectangular outline. Open frames each comprising spaced uprights 19 and 20 connected by horizontal top and bottom across members 21 and 22, are attached to the bed below the plane of discharge throat 17 as shown in Figure 3. The top cross members 21 of these open frames are connected to the shelf 18 by angle brackets 23 above the uprights 19. An angle-metal strip 25 is secured to and extends between the rear upper corners of the open frames to brace the same, and vertical columns 24 are secured to and arise from intermediate portions of said angle-strip 25 and have their upper ends suitably attached to the shelf 18. Elongated metal straps 26, performing the functions of stays, extend obliquely between and are attached to the rear edge of the shelf and to the lower portions of the uprights 20 of the open frames. A rectangular opening 27 is made in the forward portion of the shelf 18 at approximately its center of width, said opening providing egress to the receiving throat 28 at the widened upper portion of a chute 29 of somewhat S-shape. The opening 27 is of proper dimensions to receive the throat 28 that is disposed in it and projects a suitable distance above the plane of the shelf 18 as will be seen in Figures 2 and 11. This chute 29 receives the tubes 10 after they have been operated upon by the instrumentalities which form the beads upon the ends of said tubes, and said chutes convey said finished tubes to suitable mechanism that is adapted to telescope these beaded tubes with other tubes of larger dimensions.

An elongated bearing block 30 having end lugs 31 is secured to a corner portion of the shelf 18 by bolts 32 that pass through said lugs and are screwed into the shelf 18 to position said bearing block 30 parallel with a side edge of said shelf and extending rearwardly from the forward edge thereof as shown in Figures 1 and 11. There is a rectangular notch or recess 18a in the opposite corner of the shelf 18 and at the shorter side of this notch a small bearing block 33 is secured to the shelf in any suitable manner. Another small bearing block 34 is anchored to the shelf 18 opposite the inner portion of the elongate block 30. The block 33 and the alined portion of block 30

are provided with suitable bearings for journaling a horizontal elongate rotatable shaft 36 that is shorter than shaft 35 and extends beyond its bearings in block 30. The portions of the shafts 35 and 36 which project beyond block 30 have gears 37 and 38 secured to their respective ends, said gears being in mesh with each other for rotating the shafts in opposite directions. As seen in Figures 1 and 11 the shafts 35-36 are disposed parallel with respect to each other in the same horizontal plane above the shelf 18 and they are spaced apart a distance so that the throat 28 of the chute 29 is between them in a lower plane.

The intermediate portion of the shaft 35 has secured to it a pair of star-wheels which comprise disks 39 and 40 that are provided with peripheral notches 41, and said star-wheels 39-40 are maintained in separated positions by spacer spools 42 on the shaft 35. By reference to Figure 1 it will be seen that the separation of the star-wheels 39-40 is less than the length of the tube 10. The intermediate portion of shaft 36 likewise has secured to it a pair of star-wheels comprising disks 43 and 44, which are provided with peripheral notches 41a and they are maintained in spaced relation to each other by spacer spools 45 on the shaft 36. The star-wheels 39 and 43 are aligned with each other, as are also the star-wheels 40 and 44, so that the notches 41 and 41a will register with each other during intermittent rotation and pause. The adjacent peripheries of these confronting star-wheels move together in the same downward direction so that the unnotched portions of their peripheries will be substantially in contact with each other during rotation. The dimensions and proportions of the notches, which have V-shapes, are such that a tube 10 will be held between them during the beading operation which is performed upon the ends of the tube during a pause in the rotation of the shafts 35 and 36 upon which the respective pairs of star-wheels are mounted. It will be noted, by reference to Figure 11, that the discharge end 17 of the chute 16 is immediately above and it is in vertical alinement with the confronting portions of the peripheries of the pairs of star-wheels 39-40 and 43-44 so that the tubes 10 will gravitate from the chute 16 into a pair of opposing notches during a pause of the star-wheels and the tube at the next pause will have its cylindrical wall engaged at four locations while the beading elements are operating upon the tube ends.

The intermittent or step by step rotation of the star-wheels 39-40 and 43-44 is accomplished in a novel manner which will now be described. The shaft 35 beyond the bearing block 34 has a Geneva pin-wheel that is designated as a whole by the numeral 46 and has a hub that is secured to the end of shaft 35 by a transverse pin 47. The periphery of the wheel 46 is provided with sockets 48 in which radially projecting pins 49 are secured by transverse headless screws or bolts 50. Convex-surfaced rollers 51 having central bores are rotatably mounted on the radial pins 49 and they are maintained against displacement by flat heads 49a at the outer ends of said radial pins 49 which seat on shoulders 51a formed by widening the outer portions of the bores of the rollers 51.

Adjacent the Geneva pin-wheel there is a vertical shaft 52 which is surrounded by a sleeve 53 having an annular flange 54 near its lower end, which said flange rests upon the shelf 18 in the

manner shown in detail in Figure 12, where it will be seen the shaft 52 and the sleeve extend above and below the shelf 18 through a hole 55 in said shelf. A gear 56 is secured to the shaft 52 below the lower end of the sleeve 53, and beyond said gear 56 a beveled pinion 57 is attached to said shaft by a screw 58 and is in mesh with a miter-gear 58' secured to the adjacent end of a horizontal rotatable shaft 59. This horizontal shaft has bearings in the supporting frame and it has a small sprocket wheel 60 secured to an intermediate portion which is driven by a chain 61 deriving its power from any suitable actuating mechanism.

The upper end of the vertical shaft 52 projects above the sleeve 53, as shown in detail in Figure 12, where it has a Geneva-gear or modified worm 62 secured to it by means of a screw 63 that is threaded through the hub 62a. The Geneva-gear 62 is positioned relative to the Geneva pin-wheel 46 so that the periphery of said Geneva-gear 62 engages and operates between the spaced rollers 51 on the Geneva pin-wheel 46, and as shown in Figure 2 the gear 62 is disposed in a horizontal plane at a right angle to the vertical plane in the pin-wheel 46. A portion of the Geneva-gear 62 embodies a segmentally extending tongue or lip 64 and is inclined downwardly away from the body of the gear 62 where it is in position to engage between the pair of rollers 51 next succeeding the pair which have been engaged by the periphery of the Geneva-gear 62. This Geneva-gear 62 rotates in a contra-clockwise direction and the action of the tongue or lip 64 is to intermittently rotate the pin-wheel 46 and shaft 35 in a clock-wise direction when the structure is viewed in Figure 2. It will here be noted that the proportions of the Geneva-gear element 62 and its tongue or lip 64 are such that there are relatively long pauses between the spaced movements of the pin-wheel 46 and shaft 35. These periods of pause and movement are transmitted to the pairs of star-wheels 39-40 and 43-44, which star-wheels, through the medium of the gears 37 and 38 will be moved in the directions hereinbefore indicated.

The instrumentalities for rounding or beading the tube ends derive their movements from the Geneva-gear shaft 52 through the medium of a gear 65 that meshes with said gear 56 and is carried upon the lower end of a short cam-shaft 66 that projects down through its bearing 67 in the table or shelf 18 as shown in detail in Figure 12. The upper end portion of the cam-shaft 66 is provided with a cam-disk 68 that rests upon the top of bearing 67 and is provided with an eccentrically disposed headed crank-pin 69. A longitudinally reciprocable slide-bar 70 is movably mounted in spaced guides 71 and 72 that are anchored to the top of the table or shelf 18 so that said slide-bar 70 is movable towards and away from the star-wheels 39-40 in a plane midway between the vertical planes of said star-wheels as will be observed by reference to Figure 1. The end of the slide-bar 70 which is nearest the cam-shaft 66 has a pitman-link 73 pivotally connected to it by a pivot bolt 74, and the other end of said link 73 is pivotally connected to the cam-disk 68 by the crank-pin 69.

The forming dies which are adapted to bead the tube ends are preferably cylindrical blocks 75 having concave shaping recesses 76 in one of their flat end faces, such as shown in detail in Figure 7, and the other faces are provided with slots 77 to receive the adjacent end portions of swinging

rocker arms 78 that are anchored in said slots by set-screws 79. These rocker-arms 78 are provided with breaks 80 in their intermediate portions in order to position the forming dies 75 in horizontal alignment with the axis of and upon opposite sides of the tube 10 when the latter is held in operative position by the star-wheels 39-40 and 43-44. The ends of the rocker-arms 78 opposite the dies 75 are formed with disk-shaped enlargements 81 each having a central aperture 82 and a plurality of segmental or arcuate slots 83 that are concentric thereto and are utilized in adjusting the positions of the arms 78 and dies 75 with relation to the tube ends in the holding devices or star-wheels 39-40 and 43-44.

The manner of mounting the arms 78 comprises vertical pivot-studs 84, 84, disposed on opposite sides of cam-shaft 66, and provided with annular flanges 85, 85, that are secured to the shelf 18 or table 18 by screws 86, 86, and below said flanges the pivot studs 84, 84, are seated in apertures 87, 87, in said table 18. Above the flanges there are bosses 88, 88, on the pivot-studs 84, 84, which support the adjacent ends of lever-arms 89, 89, that are movably pivoted on said studs 84, 84, as shown in detail in Figure 12. Spacing spools 90, 90, that are centrally bored, are rotatably mounted on said studs 84, 84, and have their lower flanges adjustably connected to the pivoted ends 30 of the lever-arms 89, 89 by screws 91, 91; while the upper flanges of said spools 90, 90, support the adjacent enlarged pivotal ends 81, 81 of the respective die-carrying arms 78, 78, which are adjustably secured to said flanges by several 35 headed screws 92, 92, that are threaded into said flanges through the segmental slots 83 in the adjacent ends of said arms 78, 78. The assembly which has just been described is maintained against displacement on the pivot studs 84, 84, 40 bolts 93, 93, that are screwed into the ends of the pivot studs 84, 84, and have washers 94, 94, interposed between their heads and the ends of said pivot studs so that said washers will overlap the adjacent portions of the arms 78, 78.

45 It is obvious that each beading die 75 is mounted upon and actuated by a bell-crank structure which comprises a lever-arm 89, a spool 90 providing the pivotal boss of the bell-crank, and an arm 78 which carries a die 75 upon its outer 50 swinging end. The outer ends of the lever-arms 89 are operatively connected to and are moved by the reciprocating slide-bar 70 by means of links 95, 95, that converge towards each other and are connected pivotally to the slide-bar 70 55 intermediate the guides 71, 72, by a pivot bolt 96, while the opposite end of each link 95 is pivotally connected by a pivot bolt 97 to the adjacent end of a respective lever-arm 89. The reciprocatory movement of the slide-bar 70 is 60 adapted to rock the bell-crank structures, causing the dies 75, 75 to be moved into engagement with and bead the ends of the tube 10 held by the star-wheels 39-40 and 43-44; after which the dies 75, 75 are withdrawn from the tube 10 65 and the beaded tube is released and falls into the mouth 28 of the receiving chute 28.

It has hereinbefore been stated that it is an object of this invention to provide means for handling and operating upon tubes that are made of 70 paper material without damage to the paper material or distorting the shapes of the tubes. This object is accomplished by providing yieldable bearings for one of the star-wheel shafts preferably the shorter shaft 36, and in this connection reference is made to Figure 14 which shows the

structure in sectional detail. The bearing block 33 has an elongated recess or wide slot 98 extending horizontally inwardly from its end face, and the inner end 99 of said slot is of substantially semi-circular shape in section so as to act as an abutment for a bearing bushing 100 that surrounds the shaft 36 within the block. Transverse lubrication ducts 101 are made in the bushing 100, and a guide finger 102 has one of its ends screwed into said bushing while its opposite end is engaged in an aperture 103 in the adjacent portion of a face plate 104 that extends across the end of the block and is secured in place by bolts 105. A coiled spring 106 surrounds the guide pin 102 between said face-plate and the bearing bushing 100 and this spring 106 urges the bushing 100 and the shaft 36 yieldably towards the inner portion of the recess 98. A similar structure is provided at the other end of the shaft 36 in the block 30 where the corresponding face plate is indicated by the numeral 107. This arrangement permits the star-wheels 43—44, mounted on shaft 36 to yield in the event a tube 10 is improperly disposed in the respective notches of the star-wheels.

While the invention has been described in detail in its present preferred form or embodiment, it will be obvious to others who are skilled in the art, after understanding said invention, that various changes and modifications may be made therein without departing from the spirit or scope thereof. In the appended claims it is aimed to cover all such changes and modifications.

What is claimed is:

1. An apparatus for beading the ends of tubes embodying oppositely rotatable shafts; star-wheels mounted on said shafts and adapted to receive and support a tube between their marginal portions; means for rotating said shafts to dispose the tube in an operating position; forming dies positioned upon opposite sides of said star-wheels and normally spaced from the ends of the tube; bell-cranks, corresponding arms of which support said dies; and reciprocable devices operatively connected to other arms of said bell-cranks for intermittently actuating said bell-cranks whereby to engage said dies with the ends of the tube.

45

2. Apparatus for beading the ends of tubes embodying a support; shafts journaled thereon and adapted for opposite rotation; tube carrying means mounted on said shafts and adapted to move a tube to an operative position; rocker-arms fulcrumed intermediate their ends on said support with portions disposed alongside said tube carrying means; forming dies on said last-mentioned portions of said arms; a reciprocable bar mounted on said support having operative connection with said rocker-arms; and devices for reciprocating said bar whereby to engage said dies with the ends of the tube on said carrying means.

3. An apparatus for beading the ends of tubes embodying a support; shafts journaled thereon and adapted for opposite rotation; tube carrying means on said shafts adapted to move a tube to an operative position; rocker-arms fulcrumed intermediate their ends on said support with portions alongside said tube carrying means; forming dies on the last-named portions of said arms; a reciprocable bar mounted on said support having operative connection with said rocker-arms; and rotatable cam means for reciprocating said bar, whereby to engage said dies with the ends of the tube in said carrying means.

4. An apparatus for beading the ends of tubes embodying a support; shafts journaled thereon for opposite rotation; tube carrying means on said shafts for moving a tube into an operative position; rocker-arms disposed with portions alongside said tube carrying means; forming dies on the last-named portions of said arms adapted to engage the ends of the tube; a reciprocal member on said support; links connecting said member to portions of said rocker-arms for moving the latter; a rotatable shaft journaled on said support; and a crank element actuated by said shaft and having operative connection with and adapted to move said reciprocal member whereby to rock said arms to engage the dies with the ends of the tube on said carrying means.

JOHN R. McLAUGHLIN.
